United States Patent Office.

GEORGE GILL, OF TAUNTON, MASSACHUSETTS, ASSIGNOR TO REED & BARTON, OF SAME PLACE.

Design No. 3,872, dated March 1, 1870.

DESIGN FOR A TEA-SERVICE.

The Schedule referred to in these Letters Patent and making part of the same.

To all persons to whom these presents may come:

Be it known that I, GEORGE GILL, of Taunton, of the county of Bristol, and State of Massachusetts, have invented a new, useful, and ornamental Design for a Tea-Service; and do hereby declare the same to be represented in the accompanying drawing, which exhibits a side elevation of a teapot formed in accordance with such design.

The body A of the teapot is a truncated hollow ovoid, the truncation being at the upper part, where the body has a flaring rim or flange, a, to which and the mouth of the vessel A, a cover, B, may be hinged.

A fillet, b, extends about the lower portion of the body, and is joined with four or any other suitable number of legs, C C, each of which terminates in a

clawed foot, c, and is surmounted by a bust, d, in *alto-relievo*, the bust being projected from a canopy, e.

The handle D and the nose or spout E may have the forms as represented. They are to be considered as auxiliaries to the design, which embraces the truncated ovoidal body, the fillet, the legs, the busts and their canopies, arranged as exhibited in the drawing.

What I claim as my invention, is—

The said described and represented design for a tea-service.

GEORGE GILL.
